[57] CLAIM

The ornamental design for an instrument display housing or similar article, as shown.

DESCRIPTION

FIG. 1 is a front elevational view of an instrument display housing showing my new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a front elevational view of a modified form of my new design of FIG. 1 wherein the housing has been lengthened for dual instruments;

FIG. 8 is a rear elevational view thereof;

FIG. 9 is a top plan view thereof;

FIG. 10 is a bottom plan view thereof;

FIG. 11 is a front elevational view of another modified form of my new design of FIG. 1 wherein the housing has been further lengthened for three instruments;

FIG. 12 is a rear elevational view thereof;

FIG. 13 is a top plan view thereof;

FIG. 14 is a bottom plan view thereof;

The side elevational views of the two embodiments of the FIG. 1 design are identical to those of FIGS. 2 and 4.
